(57) **CLAIM**

The ornamental design for a game call speaker module, as shown and described.

DESCRIPTION

In an exemplary embodiment the nature of this product is as a game call speaker module for producing sounds that attract wildlife.

FIG. 1 is a right, top, frontal perspective view of a game call speaker module in a first or storage configuration, embodying the new design;

FIG. 2 is a right side elevational view thereof;

FIG. 3 is a left side elevational view thereof;

FIG. 4 is a front elevational view thereof;

FIG. 5 is a rear elevational view thereof;

FIG. 6 is a top plan view thereof;

FIG. 7 is a bottom view thereof;

FIG. 8 is a right, tip frontal perspective view of a game call speaker module in a second or assembled configuration, embodying the new design;

FIG. 9 is a right side elevational view thereof;

FIG. 10 is a left side elevational view thereof;

FIG. 11 is a front elevational view thereof;

FIG. 12 is a rear elevational view thereof;

FIG. 13 is a top plan view thereof; and,

FIG. 14 is a bottom view thereof.

The broken line representations of input/output connections and related structure in FIGS. 1–12 and 13; of structural ribs in FIGS. 5 and 14; of fasteners and fastener recesses in FIGS. 2, 3, 5, 9, 10, 12 and 14; and of an on/off button and indicator light in FIGS. 1, 2, 4, 5, 9, and 11–13; show use and environment, and form no part of the claim.
